UNITED STATES PATENT OFFICE.

FREDERICK W. DURHAM, OF BARNET, COUNTY OF HERTS, ENGLAND.

STEAM-GOVERNOR.

SPECIFICATION forming part of Letters Patent No. 239,469, dated March 29, 1881.

Application filed January 13, 1881. (No model.) Patented in England March 2, 1880.

To all whom it may concern:

Be it known that I, FREDERICK WILLIAM DURHAM, a citizen of England, residing at Barnet, county of Herts, England, have invented a new and useful Improved Steam-Governor, (for which I have obtained a patent in Great Britain, No. 911, bearing date March 2, 1880,) of which the following is a specification.

10 My invention relates to the construction of steam-governors for regulating the supply of steam to steam-engines, for which Letters Patent of the United States were granted to Durham and Howse, dated March 27, 1877, and to 15 Koch and Durham, dated August 12, 1878.

According to my present improvements I simplify the mechanism of the apparatus described in the specifications to the said patents by the employment of the following arrangement: The spindle, receiving motion from the steam or other motor engine, instead of being connected to the spindle carrying the revolving vanes, or to the revolving casing of the fixed vanes through sun and planet wheels, 20 or other similar mechanism, is connected thereto by the intervention of a second spindle or rod and a spring or springs, so arranged that on an increase of the speed of the driving-spindle occurring the resistance to such increase 25 offered by the vanes causes the spring to be compressed, contracted, or extended, so as to impart longitudinal motion to the second spindle or rod, or to a screwed sleeve upon it, which, in its turn, actuates the throttle valve or slide 30 of the regulating apparatus.

The arrangement of the connection of the driving-spindle by the spring to the second spindle may be variously modified. Thus, according to one arrangement, the second spindle, which passes through the hollow spindle of the vanes, passes with its one end into a hollow in the end of the driving-spindle, which has a helical or oblique slot, into which a pin or stud on the second spindle passes. To 40 this spring, or to a projection thereon, is connected the one end of a helical or volute spring, the other end of which is connected to the vane-spindle, so that the driving-spindle drives the vane-spindle through the second spindle

and spring. Thus, on an increase of speed of 50 the driving-spindle occurring, the spring, in being contracted by reason of the relative motion between the driving-spindle and vane-spindle, imparts longitudinal motion to the second spindle by causing its stud to slide in 55 the oblique slot, and this spindle consequently imparts motion to the slide of the controlling-cylinder, to which it is, by preference, directly connected by a connection permitting its free 60 rotation.

Instead of using an oblique slot or groove in the driving-spindle, this may be provided with a screw-thread of quick pitch working upon or within a screw-thread on the second spindle; or the latter may be provided with a 65 screw-thread working within an internal screw-thread on the hollow vane-spindle, through which it passes.

In the drawings, Figure 1 is a side view, Fig. 2 a plan, and Fig. 3 a part longitudinal section, of the arrangement of the before-described apparatus which I employ by preference.

The shaft A, the pulley B of which is driven by the engine, has a cylindrical barrel, C, on its end, into which passes the one end of a spindle, D, the other end of which carries the cylindrical casing E, containing liquid, within which are the stationary valves F, carried by the spindle G. The barrel C of the shaft A is connected to the spindle D by means of a volute spring, H, the inner end of which is connected to D, while the outer end is connected to C. The spindle D is formed with a screw-thread outside the barrel C, on which is a screwed sleeve 85 or nut, I, connected to C by slotted arms I', through which pass top bolts or pins, C', screwed into C, so that while I is carried round by C it is free to slide or work to and fro on D. The sleeve or nut I has a groove, I'', into which 90 takes a pin on one arm of a bell-crank lever, K, having its pivot at K', and taking with its other arm into a groove on the slide-valve rod L of the steam-cylinder L'. From this arrangement it will be seen that when rotary motion 95 is imparted to the shaft A and barrel C in the direction of the arrow, Fig. 1, this motion will be imparted through the spring H to the spin-

dle D and casing E, a certain resistance to the rotation of which is offered by the stationary vanes F acting in combination with the liquid in the casing. On an increase of speed of the 5 spindle A taking place, the barrel C will turn somewhat relatively to the spindle D, on account of the resistance offered by the casing E to any sudden increase of the speed of D, and as C carries the sleeve or nut I round with 10 it, it follows that this sleeve or nut will be screwed forward somewhat in the direction of the arrow upon D, thereby causing the lever K to depress the slide-rod L of the cylinder L', so as to admit steam into the latter and cause 15 its piston-rod M to actuate the throttle or other valve of the steam-supply pipe of the engine to which it is connected, thereby reducing the speed of the engine again.

The sensitiveness of the apparatus to any 20 increase of speed may be accurately adjusted to any required degree by adjusting, in the first instance, the tension of the spring-connection at H between A and D. This is effected by removing the screws C' and turning 25 C round upon D until the spring H has acquired a certain amount of tension, whereupon the screws C' are passed through the slotted arms of I, and are screwed into whichever of the holes in C are then situated at those points, 30 the screw-threads of D and I now preventing C from being turned back again upon D. Furthermore, the slide-valve rod L is held up so as to keep the slide-valve in the closed position by means of a spring at N, the tension of 35 which is regulated by a screw, N', so that the slide-valve rod offers a certain regulated amount of resistance to the downward motion which the lever K tends to impart to it on an increase of speed taking place. A scale, O, is 40 provided on the guide of the slide-valve rod, and an index is connected to the spring, as shown, by means of which the latter may be set to the exact tension corresponding to the number of revolutions constituting the normal 45 speed of the engine.

The apparatus is also made to indicate the 50 number of revolutions actually performed by the engine, by connecting the spindle G of the vanes F to the one end of a volute spring, P, the other end of which is attached to a fixed 55 barrel, Q. The outer face of this barrel is formed as a graduated dial, as shown in front view at Fig. 4, and the end of the spindle G carries a pointer, R.

It will be readily understood that as the 60 resistance of the vanes to the rotation of the casing E at a certain speed of the engine will produce a certain degree of tension in the spring P, causing the spindle G, and consequently pointer R, to turn to a corresponding position in the barrel, then, on any increase of speed taking place, and consequently also of the resistance, the spindle G will turn somewhat farther, so as to put a corresponding increased tension on the spring, and the pointer 65

will be made to turn in a corresponding manner upon the dial.

The steam-cylinder L' is mounted on the framing by a trunnion, L², the axis of which coincides with the axis of the slide-valve rod 70 L, so that it can be turned round into any position that may be required for connection with the steam-admission valve of the engine.

Having thus described the nature of my invention and in what manner the same is to be 75 performed, I claim in respect of apparatus for regulating the supply of steam to steam-engines—

1. A shaft driven by the engine, connected by a volute or other spring to a spindle whose 80 rotation is resisted by the action of a casing containing liquid and vanes, either one of which is stationary while the other revolves, the said spindle having a screw-thread on which is a screwed sleeve or nut having a sliding connection to, but revolving with, the driving-shaft, so that on the latter being turned relatively to the screw-threaded spindle the sleeve or nut will slide upon the spindle and impart motion to the slide-valve rod of a steam- 85 cylinder actuating the steam-admission valve of the engine, substantially as herein described.

2. The shaft A, driven by the engine, connected by a spring, H, with the screw-threaded 90 spindle D, driving the casing E of the resisting-fan, while a screw-threaded nut or sleeve, I, on the spindle D, carried round by the shaft A by a sliding connection, I', is connected by a lever, K, to the slide-valve rod L of a steam-cylinder, L', actuating the throttle-valve of the engine, so that by a differential motion 95 between shaft A and spindle D the sleeve or nut I will be worked forward, so as to move the slide-valve rod L and cause the piston-rod M of the cylinder L' to actuate the throttle-valve.

3. The combination of the shaft A, barrel C, spring H, screw-threaded spindle D, connected to the resisting-fan, screw-threaded nut or sleeve I, lever K, slide-valve rod L, and adjustable spring-connection N N', all arranged and operating as herein set forth.

4. The combination of the shaft A, barrel C, spring H, screw-threaded spindle D, screw-threaded nut or sleeve I, casing E, vanes F, spindle G, connected by spring P to casing Q, and having a pointer, R, working over a graduated dial of the said casing, all arranged and operating as herein set forth.

5. The combination of the shaft A, barrel C, spring H, screw-threaded spindle D, and screw-threaded nut or sleeve I, connected to barrel C by slotted arms I', and screws C', capable of being screwed into different holes on the circumference of C, for the purpose of adjusting the tension of the spring-connection 125 between the shaft A and spindle D, as herein described.

6. In combination with the screw-threaded 130

sleeve or nut I, lever K, and slide-valve rod L, the cylinder L', mounted on a trunnion, L², whose axis is in line with the axis of the slide-rod, so that the cylinder can be turned into any desired position for connection with the throttle-valve.

In testimony whereof I have signed my name to this specification, in the presence of two sub-

scribing witnesses, this 15th day of December, A. D. 1880.

FREDERICK WILLIAM DURHAM.
